UNITED STATES PATENT OFFICE.

STALEY D. POOLE, OF MOLINE, ILLINOIS, ASSIGNOR TO DEERE & COMPANY, A CORPORATION OF ILLINOIS.

PLOW.

1,181,345.

Specification of Letters Patent.

Patented May 2, 1916.

Application filed July 27, 1908. Serial No. 445,629.

To all whom it may concern:

Be it known that I, STALEY D. POOLE, a citizen of the United States, residing at Moline, in the county of Rock Island and State of Illinois, have invented certain new and useful Improvements in Plows, of which the following is a specification, reference being had therein to the accompanying drawing.

10 The invention relates to engine gang plows. As commonly constructed, plows of this class comprise a main frame adapted to be coupled to a traction engine, and a series or gang of plow bottoms more or less 15 flexibly connected to the said frame.

One of the objects of my invention is to produce a plow of the class referred to so constructed that the individual plowing units shall possess sufficient flexibility to insure 20 plowing of uniform depth in uneven ground and, at the same time, the structure as a whole shall have enough rigidity to insure the level running of the units and to maintain them in proper relation to each 25 other.

Another object of my invention is to provide manual means for raising and lowering the plowing units of such a character that the plow can be handled with ease and with 30 economy as to labor.

Another object is to construct a plowing apparatus of the class referred to, in such way that a rear trailing plowing unit connected by a fixed (though adjustable) hinge 35 at the front end can have the bottom plane of the body adjusted vertically and also have the body so adjusted angularly with respect to longitudinal horizontal lines that the bottom will always tend normally to enter the 40 earth, though resisted by a gaging or pressure-taking wheel situated close to the body.

Another object of my invention is to construct the plow frame with detachable sections by means of which said frame can be 45 expanded or contracted and the number of plow bottoms increased or diminished correspondingly.

The above objects and various others more or less incidental or ancillary to them will be 50 clearly understood from the following description in connection with the accompanying drawings, as will also the features of construction which I employ to attain these objects.

55 In the drawings, Figure 1 is a plan view

of a plow constructed in accordance with my invention, and of the rear part of a traction engine to which the plow is connected. Fig. 2 is a left side elevation of the plow shown in Fig. 1. Figs. 3 and 4 are plan views of detachable sections of the plow frame. Fig. 5 is a side elevation of one of the two-bottom gangs which I employ. Fig. 6 is a plan view of said gang.

Referring in detail to the construction 65 illustrated, 1 indicates a traction engine of which only a portion of the rear platform and drive wheels is shown.

2 indicates the main plow frame as a whole and 3, 3, a series of individual plow 70 elements or units or gangs which are connected to the frame 2.

The main frame 2, which is approximately triangular in outline, is preferably built up of structural steel, the front member 4, the 75 left side members 5 and 6 being preferably channels, the long or diagonal side member 7 being preferably a plate, while most of the other structural members are angle bars, which serve to brace the frame. The adjacent ends of the structural members are 80 rigidly united by plates 8, 8, to which the bars are riveted or bolted.

The particular arrangement of the various angle bars is clearly shown in the drawing 85 and need not be described in detail, but it will be noted that, a series of transverse bars 9, and a series of longitudinal bars 10 are arranged at right angles to each other, so as to form a series of off-sets projecting beyond the plate 7 of the frame, which off-sets are provided with coupling devices, 90 presently to be referred to, to receive the individual plow gangs.

The main frame is supported from the 95 ground by three runners 11, 12 and 13, these runners having flat ground-engaging shoes of sufficient width to insure the proper support of the frame even on soft ground. The forward up-turned ends of these runners are 100 secured directly to the frame, while the rear ends are connected with the frame by uprights as 11^a, 13^a.

The main frame proper is constructed to receive ten plow bottoms, but in order that 105 the capacity of the plow may be increased if desired, I have devised detachable extensions for the frame, one of these extensions 14 being designed for attachment to the rear left corner of the frame and the other 110

extension 15 being designed for attachment to the right forward corner of the frame. These extensions 14 and 15 are shown in Figs. 3 and 4, and it will be seen that they 5 are composed of structural steel, the extension 15 consisting essentially of a heavy angle bar, while extension 14 is made up of angles and plates rigidly united by rivets or bolts. The extensions are provided with 10 bolts by means of which they can readily be connected with the main frame, and which permit their easy removal when it is desired.

The main frame proper is covered by a 15 plank platform 16, the outline of which is shown by broken lines in Fig. 1. The parts of the transverse angle bars 9 which extend beyond the long or diagonal side of the frame, and also the extensions 14 and 15 20 are provided with angle irons 17 which are perforated so as to form clevis connections for the plow gangs 3.

One of the plow gangs 3 is illustrated on an enlarged scale in Figs. 5 and 6, and it 25 will be seen that it comprises a rigid, substantially rectangular frame 18 to each side of which is secured one of the plow bottoms 19, thus forming a two-bottom gang, which experience has shown is more 30 satisfactory for many classes of work than a gang with any other number of bottoms. Each of the individual gangs is provided with a ground wheel 20 which performs the double function of a depth gage and a lifting 35 device, as will presently appear. The wheel 20 is mounted upon a swinging arm preferably though not necessarily in the form of a bail 21, the rear ends of which are pivotally mounted in brackets 22, which 40 are secured to the sides of the gang frame 18. A long upwardly and forwardly extending hand lever 23 is pivotally mounted on the gang frame, the lower part of said lever being preferably formed in two parts 45 which diverge forming arms 23^a, the ends of which are pivoted preferably on the ends of the bail 21. This hand lever 23 is connected to the wheel 20 by means of the forked arm 24, which embraces the wheel 50 and engages the bail 21, upon which the wheel is mounted, and the upper end of which is pivotally connected to said hand lever. It is clear that by moving the hand lever up and down, the wheel 20 will be 55 correspondingly raised and lowered. To hold the hand lever and with it the wheel 20 in adjusted position, the toothed segment 25 is provided. This segment is secured at its lower end to a cross brace 26 of the 60 frame 18 and at its upper end is supported by bars 27 which diverge at their lower ends to connect with the sides of the frame 18. The hand lever 23 is provided with a suitable thumb latch device 28, which coöperates 65 with the notched segment 25 to hold

said lever in adjusted position. A coil spring 29 is secured at one end to an arm 23^b on the lever 23 and at its other end to up-standing lug 26^a on the cross brace 26. The tension of this spring, it will be seen, tends 70 to swing the bail 21 and wheel 20 downward. Connected to the bottom or frame is a vertical spindle 18^a upon which can be mounted when desired a rolling colter of any suitable or well known construction. 75 The frame 18 is provided at its front end with forwardly extending arms 30, which are adapted to be received between the clevis brackets 17 of the main plow frame, said brackets 17 and the arms 30 being perforated 80 as at 30^a to receive transverse coupling pins 31. A relatively wide two-point connection is thereby formed, which while it permits the individual plow gang to rise and fall freely, holds the gang securely against side 85 swinging, and also insures the level running of the plow bottoms. The two pivot points are in substantial longitudinal alinement with the landside parts of the plow bottoms, thus providing for the transmission of the 90 draft from the frame to the bottoms along lines located in longitudinal vertical planes.

I herein refer to the plow "bottom" and mean to be understood as thereby indicating the mold board, the share, the frog, and the landside, these being the parts that are directly at work upon the earth during the 95 process of plowing.

As shown, each of the arms 30 is provided with two perforations or apertures 30^a at the 100 forward end, each of these apertures being adapted to receive one of the coupling pins 31. Whenever it is desired to change the line of draft, or change the working angle 105 of the bottoms with respect to horizontal planes, this can be readily accomplished by withdrawing the coupling pins 31, then moving the front ends of the arms 30 up or down, and reinserting the pins. The main frame remains constantly fixed as to the 110 surface of the ground, and, consequently, when the front ends of the bars 30 are moved up or down in relation to the frame, the line of draft will be varied, and the dip of 115 the plow body can be correspondingly modified so as to vary the suction as desired. The lowering of the plow points to even a slight extent will materially increase the tendency of the body to enter the soil, and because of this, there can be assurance that 120 it will always enter to the depth desired, as it can be adjusted so as to even tend to penetrate to a greater depth than is desired. This latter tendency is, however, overcome 125 by means of the wheel 20 and its adjusting and fastening devices. Thus, if the working angle of the plow bottom (resulting from the adjustment at the front end of the beam or plow frame) is such as to cause a penetration of the body to a depth of eight 130

5 inches or ten inches under all circumstances, and it be, at the same time, desired to plow only to the depth of six inches, the wheel 20 can be set at the proper point to insure a cut 5 of six inches deep. If the plowman observes circumstances where it is desirable to cut deeper, as eight or ten inches, he can adjust the wheel 20 to accomplish it, or, vice versa, if he, at places, desires to produce a 10 shallower cut, say one of four inches, he adjusts the wheel 20 in the opposite direction. That is to say, by having the two adjustments, one (here at the front end of the beam for changing the working angle), and 15 the other at a point near the plow body, he can first so relate the parts that the body to raise or lower it shall constantly tend to enter the ground, and can then as circumstances demand, attain the depth of cut desired. 20 The wheel 20 and its adjuncts not only constitute a lifting mechanism, in the sense of a mechanism for bringing the plows entirely out of the ground and supporting them in elevated positions, but can be regarded as the pressure-taking means for receiving the surplus force which tends to carry the plow body down into the ground beyond its predetermined depth.

25 The two adjustments referred to provide for the meeting of the widely differing conditions of soil and variations of ground surface, and also enable the plowman to overcome the difficulties incident to the wear rapidly experienced by these implements, 30 and particularly along those lines of the metal parts which lie in the bottom horizontal plane of the share, the point and the landside.

35 The wheel 20, with its operating and holding devices, is not a gage wheel in the sense that it is depended on for, or even assists in, fixing the working angle or the line of draft of the plow body. It has been quite common to employ ground engaging 40 wheels in connection with plow beams, and arranged either directly at their front ends or relatively near those ends, so that, as they are moved up or down in relation to the beam, the dip of the plow body and its 45 tendency to enter the earth or come out of it are correspondingly modified. But in the present machine, this wheel 20 is placed close to the transverse line of the plow body, and its action in adjusting the plow as to 50 the working angle or the line of draft can be regarded as negligible. It is here merely a rolling support which can be thrown into different positions in relation to the beam and the body so as to take their down thrust, 55 the devices at the front end of the beam being depended on for varying the line of draft. And I believe myself to be the first to combine the following elements: (1) a vertically fixed gang frame on ground supports 60 which constantly hold it substantially uni-

formly in relation to the surface of the ground; (2) a series of plow beams or frames each extending rearward from this main frame; (3) adjustable hinging or pivoting devices at a single axis only at the 70 front end of each beam normally fixed in relation to the main frame so that there is no loose vertical play at the front end of the beam; (4) means for adjusting the working angles of the bottoms as by holding the 75 pivot devices at one horizontal line or another relatively to the vertically fixed main frame; (5) an abutment wheel immediately adjacent to the plow bottom upon which it can be lifted directly upward through the 80 earth without any tilting or rocking thereof around a transverse axis through or near the bottom; and (6) means, near the bottom, such as a lever, for exerting force downward 85 on the wheel against the ground at points near the bottom to lift the latter bodily up through the earth. The plowing element provided by this assemblage of parts enables me to accomplish important ends not attainable without each and all of them. 90

95 I have illustrated only two hinge apertures in each of the downward turned arms 30, having found that under ordinary circumstances these give me sufficiently wide range of vertical adjustment for the lowermost planes of the bottom, that is, adjustment of the line of draft. When both of the hinge pins 31 are in their uppermost holes the tendency is to give the plow its greatest suction, and when so adjusted the point and share will tend to descend practically indefinitely. On the other hand, when the hinge pins are in their lowermost apertures, the tendency is to so elevate the line of draft 100 relative to the lowermost plane of the bottom, that the suction of the point and share will not carry them down normally more than, say, five or six inches, and the plowman can reduce this depth to two or three inches if he desires for a longer or a shorter 105 time by means of the ground-abutting or pressure-taking action of the wheel 20, although the suction is still present and tending to take the plow bottom deeper. When he desires to plow unusually deep, say, eight 110 inches or more, he places the hinge pins in the upper apertures in the bar 30, which will cause the plow point to enter the earth, say, twelve or fourteen inches, and then he secures any lesser depth he desires by means 115 of the pressure wheel 20 adjusted to resist the excess of suction. 120

125 I employ but one pressure taking or lifting wheel 20 for two of the bottoms, thus greatly reducing the number of parts that have been required in gang plows of this type as heretofore constructed, these parts including wheels (of twice the number of mine) and the carriers, links, guides, levers, etc., that are used in conjunction therewith. 130

The greater labor incident to lifting, at once, two of the bottoms, instead of one, is compensated by so arranging the wheel, its bail and its hand lever, that the force of the draft (from the tractor or engine) can be utilized to assist the plowman in quick liftings and adjustments, the wheel tending as soon as unlocked to roll backward and bring the bail toward a vertical position under the force of the draft. The spring 29 also assists in this compensation, and provides a resilient support upon which the beam and plow bottoms (when the lock is released) have a species of floating action, the spring insuring quick response to the movements of the levers. The spring, the wheel, the bail and the lever are so arranged that when the spring is exerting its greatest force, the force from the draft is less efficient. Again, the spring is in that part of the range of its work where it is most efficient when the suction of the plow bottom (its general penetrating tendency) increases in efficiency; that is to say, their relations are such that the increasing resistance to the lifting action caused by the suction is balanced by an increasing tension in the spring. If the lifting action is continued long enough the plow is elevated entirely from the ground and can be fastened in its upper position, this being desirable when turning at the furrow end or during transportation from place to place. The fixity of the axial line at the front end of the plow beam or frame (after the hinge devices have been adjusted) is of great importance, as the beam is thus held at that end against any sagging or whipping, vertically, and the bottom will not rock around the wheel to vary the line of draft.

What I claim is:

1. In a plowing apparatus of the class set forth, the combination of a main frame adapted to be coupled to a tractor and mounted in fixed position relatively to the surface of the ground, and a gang of plowing elements each comprising one or more bottoms, a bottom-carrying bar or beam rigid with the bottoms and pivotally connected directly to the main frame at a single axis interposed between the bottom and the main frame, a forward and downward extending swinging bail mounted on each carrier, a wheel mounted on said bail and adapted to bear against the ground at points near the plow bottoms, and a hand lever mounted on the bottom carrier independently of the main frame and adapted to swing the bail and wheel longitudinally of the machine, substantially as set forth.

2. In a plowing apparatus of the class set forth, the combination of a main frame adapted to be coupled to a tractor and mounted in fixed position relatively to the surface of the ground, and a gang of plow-

ing elements each comprising one or more plow bottoms, a bottom-carrying bar or frame formed with two relatively widely separated front end parts, means for hinging each of the front end parts directly to the main frame at a single axis interposed between the bottoms and the main frame, a forward and downward extending swinging bail mounted on each carrier, a wheel mounted on said bail and bearing against the ground at points adjacent to the bottoms, a hand lever mounted on the beam or frame and connected rigidly to the bail for moving the ground wheel backward and forward for varying the position, vertically, of the beam and bottom, and means for locking the wheel in position after adjustment, substantially as set forth.

3. In a plowing apparatus of the class set forth, the combination of a main frame adapted to be coupled to a tractor and mounted in fixed position relatively to the surface of the ground, and a gang of plowing elements, each comprising two reciprocally steadyng plow bottoms, a bottom-carrying beam or frame rigidly connected to both of said bottoms and having at its front end two relatively widely separated pivotal connections uniting it directly with the main frame at a single axis which is the only axis for said beam between the plow bottoms and the main frame, a forward and downward extending swinging bail on the said beam or frame, a wheel mounted on said bail and bearing against the ground at points relatively close to the bottoms, and a lever mounted on the beam independently of the main frame and connected to the said bail for moving the rear end of the beam vertically around the beam axis at the main frame, substantially as set forth.

4. In a plowing apparatus of the class set forth, the combination of a main frame adapted to be coupled to a tractor and mounted in fixed position relatively to the surface of the ground, and a gang of plowing elements each comprising two reciprocally steadyng plow bottoms, a bottom-carrying beam or frame rigidly connected to the bottoms and pivotally connected directly to the main frame at points in the vertical longitudinal planes of the landside parts of the bottoms, substantially as set forth, whereby there is but a single hinge axis for the bottom relatively to the main frame, a vertically movable ground wheel mounted on the beam and bearing upon the ground at points near the bottoms on a longitudinal line midway between the furrows of the two bottoms, a lever mounted on the beam independently of the main frame for moving the ground wheel vertically, and means for locking the wheel after adjustment.

5. In a plowing apparatus of the class set forth, the combination of a main frame

adapted to be coupled to a tractor, and a gang of plowing elements each comprising one or more plow bottoms, a bottom-carrying bar or frame rigidly connected to the bottoms, and pivotally connected at a single axis directly to the main frame whereby said beam and bottoms move vertically in arcs fixed in relation to the main frame, a forward and downward extending swinging bail or arm mounted on each carrier, a wheel mounted on each bail and bearing against the ground at points adjacent the bottoms, and means for swinging each bail and wheel vertically whereby the beam and the bottoms are held and moved in the said fixed arcs.

6. In a plowing apparatus of the class set forth, the combination of a main frame adapted to be coupled to a tractor and mounted in fixed position relatively to the surface of the ground, and a gang of plowing elements comprising one or more plow bottoms, a bottom-carrying beam or frame having at its front end two relatively widely separated points of pivotal connection united directly with the main frame at a single axis about which the beam or frame can vibrate vertically in arcs fixed relatively to the frame, a vertically swinging bail or arm mounted on each carrier, a ground wheel mounted on said bail and bearing against the ground at points relatively near the bottoms, means for swinging each bail and wheel vertically and means for locking them after vertical adjustment.

35 7. In a plowing apparatus of the class set forth, the combination of a main frame adapted to be coupled to a tractor, and a gang of plowing elements each comprising two reciprocally steadyng plow bottoms, a bottom-carrying beam or frame having a transversely extended two-point pivotal connection uniting it directly with the main frame at a single axis which is fixed relatively to the ground surface and about which the beam and bottoms can swing while held in fixed arcs, a swinging bail or arm mounted on the plow beam or frame, a ground wheel on the bail bearing against the ground at points near the bottoms, means for swinging the bail and wheel vertically, and means for holding them in position after adjustment.

8. In a plowing apparatus of the class described, the combination of the following elements, namely, a main frame mounted in fixed position relatively to the ground, a plow bottom, a bottom carrying beam or frame rigidly connected to the bottom and secured to said main frame at a single axis between the bottom and the main frame, and which is vertically fixed, a pressure-receiving wheel mounted on the beam immediately adjacent to the bottom, and means independent of said wheel for varying the working angle of the bottom.

9. In a plowing apparatus of the class described, the combination of a main frame mounted in fixed position relatively to the surface of the ground, a plow bottom, a bottom-carrying beam or frame rigid with the bottom and directly secured to the frame by a vertically fixed pivot around which the beam and bottom swing vertically while held in fixed arcs, a vertically adjustable wheel mounted on the beam at points adjacent to the bottom, means for holding the front end of the beam in different positions vertically to vary the working angle of the bottom, and means extending to the platform for moving the wheel vertically.

10. In a plowing apparatus of the class described, the combination of a main frame fixed in position relatively to the surface of the ground, a plow bottom, a bottom-carrying beam or frame secured to the main frame by vertically adjustable hinging devices at a single axis normally fixed in relation to the main frame and around which, after adjustment, the bottom can be moved vertically in fixed arcs, a vertically adjustable wheel mounted on the beam, and means for moving said wheel vertically, substantially as set forth, whereby the bottom can be lifted upward through the earth without substantially modifying its line of draft.

11. In a plowing apparatus of the class described, the combination of a main frame mounted in fixed position relatively to the ground, a plow bottom, a bottom-carrying beam or frame secured to the main frame by a vertically adjustable hinging connection having a single axis between the bottom and the main frame and which is normally fixed, whereby the bottom is held in fixed radial position relatively to the main frame, a vertically movable ground abutting wheel under the rear end part of the beam, and power-applying devices for forcing the wheel vertically without affecting the radial relationship of the plow bottom to the hinge after the vertical adjustment of the latter.

12. In a plowing apparatus of the class described, the combination of a main frame mounted in fixed position relatively to the ground, a plow bottom, a bottom-carrying beam or frame rigidly connected to the bottom, a horizontal hinge connection between the front end of the beam and the main frame, the beam being movable as a rigid integer from end to end around the axis of the said hinge connection, means for varying the working angle of the plow bottom, a ground support for the bottom independent of the main frame and connected to the beam at its outer end, and means mounted on the beam for drawing the plow bottom bodily upward through the earth, substantially as set forth.

13. In a plowing apparatus of the class

described, the combination of a main frame mounted in fixed position relatively to the ground, a plow bottom, a bottom-carrying beam or frame secured at its rear end to the bottom and at its front end pivotally connected directly to the main frame by a hinge connection having a vertically adjustable axis around which, after adjustment, the plow bottom is movable vertically in fixed arcs, a vertically movable wheel mounted on the beam and bearing against the ground at points adjacent the plow bottom, and means for forcing the said wheel downward, substantially as set forth.

14. In a plowing mechanism, the combination of a draft frame, a plow beam connected at its forward end with the frame for movement vertically in fixed arcs about a transverse axis normally fixed in relation to the ground surface, a plow bottom connected to the rear part of the beam, a relatively vertically movable ground-engaging wheel near the bottom on which the beam and bottom are normally connected in fixed relation to the ground surface, and an automatically acting beam lifter having a relatively fixed abutment on the beam and having a connection with the relatively movable wheel for applying force tending to move the wheel downward with respect to the beam and thereby lift the beam and bottom.

15. In a plowing mechanism, the combination of a draft frame, a plow beam connected at its forward end with the frame for movement vertically in fixed arcs about a transverse axis normally fixed in relation to the ground surface, a plow bottom connected to the rear part of the beam, a relatively vertically movable ground-engaging wheel near the bottom on which the beam and bottom are normally carried in fixed relation to the ground surface, a power device connected to automatically apply force tending to move the wheel downward with respect to the beam and thereby lift the beam and bottom, and manually releasable means for normally holding the power device out of action.

16. In a plowing mechanism of the class set forth, the combination of a main frame adapted to be coupled to a tractor and mounted in fixed position relatively to the ground, a gang of plowing elements trailing behind said frame and each comprising a pair of rigidly connected plow bottoms, a bottom carrying rectangular frame formed with longitudinal side bars extending respectively from the plow bottoms to the main frame, and with cross bars rigidly connected to the side bars, and with extensions projecting forward from the side bars providing two widely separated hinge elements, respectively, approximately in the longitudinal vertical planes of the plow bottoms, means for hinging the said extensions directly to the main frame, a ground support independent of the main frame for the rear part of the rectangular plow frame, and means carried by the plow frame for vertically adjusting said support, substantially as set forth.

17. In a plowing apparatus of the class set forth, the combination of the main frame, the ground support therefor arranged to hold it in fixed position relatively to the ground, a gang of plowing elements trailing rearward from said frame, each having a plow-carrying frame connected at its front end only to the main frame, said connection being a hinge, and having an adjustable ground support at its rear end independent of the main frame, a frame section supplemental to the main frame aforesaid, means for rigidly securing the supplemental section to the main frame to hold it in rigid relation thereto and in the same relation to the ground, and supplemental plowing elements similar to those aforesaid and pivotally connected to the supplemental frame section, substantially as set forth.

In testimony whereof I affix my signature, in presence of two witnesses.
